UNITED STATES PATENT OFFICE.

MARIE LUDOVICA SHEPPARD, OF ISLINGTON, EXECUTRIX OF JAMES SHEPPARD, DECEASED, AND BERTRAM CHATTERTON, OF LONDON, ENGLAND; SAID MARIE LUDOVICA SHEPPARD, EXECUTRIX, ASSIGNOR TO SAID CHATTERTON.

FIRE-EXTINGUISHING INSTALLATION.

No. 920,885.

Specification of Letters Patent.

Patented May 4, 1909.

Application filed December 7, 1908. Serial No. 466,387.

To all whom it may concern:

Be it known that JAMES SHEPPARD, late a subject of the King of Great Britain, and formerly residing at Trayshill, Hornsey Lane, 5 Islington, in the county of Middlesex, England, deceased, and BERTRAM CHATTERTON, a subject of the King of Great Britain, residing at 10 Mundania road, Honor Oak, London, England, have invented new and useful 10 Improvements in Fire-Extinguishing Installations, of which the following is a specification.

This invention relates to fire extinguishing apparatus of the kind in which compressed air is used for discharging water or other liquid for the purpose of extinguishing a fire.

Hitherto it has been proposed to use a vessel stored with compressed air, and to utilize the same to discharge the contents of one or 20 more water tanks not normally under pressure into a system of pipes laid about a building having convenient orifices or hydrant cocks to which the ordinary hosing provided with a nozzle may be connected; or the 25 separate air vessel has been dispensed with and the water tank used to contain both the water and compressed air. In known apparatus of this kind the following disadvantages are present:—(a) When a fire occurs, 30 two cocks have to be turned on, the air cock and the hydrant cock. (b) The compressed air has to force the water under pressure from the tank to the hydrant which on account of fluid friction especially in the bends 35 involves the use of large water pipes in the fixed or permanent installation, and results in a costly and unsightly installation. (c) There is danger of frost breaking the pipes when full of water.

40 According to the present invention a number of closed tanks or vessels, filled with water, are arranged in positions suitable for the command of property to be protected, for example, on the several floors or in different 45 parts of a building, and each tank is provided with a discharge pipe that starts from near the bottom of the tank and rises above the level of the water in the tank whereby a valve for retaining the water in the tank is 50 rendered unnecessary. The water is discharged when required by air supplied under pressure from a suitable reservoir.

This improved system of fire extinguishing appliance, avoids the objections above set forth, and is adapted to secure at any 55 moment an instant discharge from any level of a stream of water at full pressure. In this arrangement all the fluid conduits stand charged with air only, and the danger of water freezing in the pipes is eliminated. 60 Moreover, comparatively small pipes suffice to convey the air to the water tanks, and bends in these pipes do not prove objectionable. The water tanks or vessels are only of sufficient capacity to extinguish fire at the 65 outset, and take the place of pails, hand pumps, chemical fire extinguishers and the like. The improved system moreover provides for the almost instant application of water to a fire by opening only one air cock, 70 there being no water cock as in previous proposed systems. The whole system when not in use lies in a state of readiness, and is proof against many of the accidents liable to occur in other systems where water is discharged 75 by the agency of compressed air.

Referring to the annexed drawing which shows diagrammatically the essential parts of an installation of fire appliances for a building or the like arranged according to the 80 present invention, *a*, *a* are closed water tanks or vessels placed at selected points where fires are most likely to break out. Each tank *a* is provided with a single discharge pipe *b* starting from near the bottom of the 85 water tank and rising above the level of the water in the tank. In the preferred construction the pipe *b* passes out through the top of the tank as shown. The outer end of each pipe *b* is adapted to be fitted with a 90 length of hose terminating in a suitable discharge nozzle (not shown in the drawing) as will be readily understood.

e is a vessel containing air under pressure. Said vessel communicates with the water 95 tanks *a* by tubes *f*. Adjacent to each water tank is a stop valve *d* which is normally closed so that the tanks *a* are not normally under pressure, but immediately one of the valves *d* is opened the air under pressure can 100 enter the corresponding tank and discharge the liquid through the outlet pipe *b*. The air vessel *e* may be situated either above or below the level of the tanks *a*. The air is

pumped into the vessel *e* through an admission tube *g*, provided with a non - return valve *k*.

h is a pressure gage and *j* is a safety valve.

5 A stop valve *c* may be provided as shown, to allow of shutting off the pressure when desired from all of the pipes *f*, but this valve is kept normally open.

10 The above described arrangement of apparatus permits the withdrawal of liquid only by admitting air to one or other of the tanks *a* on opening the corresponding valve *d*, and it is not necessary to provide the outlet pipe *b* with a stop valve. Should any 15 water be withdrawn from any of the tanks the effect will be denoted by a reduction of pressure indicated on the pressure gage. A check is thus placed upon the unauthorized withdrawal of water from the tanks *a*.

20 It is obvious that a gas other than air may be used in the pressure vessel *e*, and also

that chemically treated water or other liquid may be used in the tanks *a* in lieu of pure water.

What is claimed is:

In a fire extinguishing installation, a plurality of water tanks, a compressed air vessel, tubes connecting the said compressed air vessel to the tanks, stop valves in said tubes, respectively controlling the supply of 30 compressed air separately to each tank, and valveless discharge pipes respectively leading from near the bottom of each tank and rising above the level of the water therein.

MARIE LUDOVICA SHEPPARD,
Executrix of the late James Sheppard.
